UNITED STATES PATENT OFFICE.

CHARLES R. NELSON, OF CHICAGO, ILLINOIS.

LOOSE-LEAF BINDER.

SPECIFICATION forming part of Letters Patent No. 760,799, dated May 24, 1904.

Application filed August 1, 1903. Serial No. 167,923. (No model.)

To all whom it may concern:

Be it known that I, CHARLES R. NELSON, a citizen of the United States, and a resident of Chicago, county of Cook, and State of Illinois, 5 have invented certain new and useful Improvements in Loose-Leaf Binders, of which the following is a specification and which are illustrated in the accompanying drawings, forming a part thereof.

10 This invention relates to that type of loose-leaf binders which are especially adapted for use in connection with what is popularly known as the "loose-leaf" ledger and comprising a rigid back having hinged sides, to which impaling-hooks are attached for passing through the leaves.

The object of the invention is to provide a simple, cheap, and efficient mechanism for controlling and securing the hinged sides; and 20 it consists of the structure hereinafter described and which is illustrated in the accompanying drawings, in which—

Figure 1 is a detail plan view of the binder with its covers open. Fig. 2 is a detail plan 25 view of the back of the binder. Fig. 3 is a detail section on the line 3-3 of Fig. 2. Fig. 4 is a detail end elevation of the back. Fig. 5 is a detail cross-section taken on the line 5-5 of Fig. 1, showing the binder open. Fig. 6 is 30 a similar view, the binder being closed; and Fig. 7 is a view similar to Fig. 1, showing a slightly-modified construction.

The back of the binder when closed is substantially in the form of an oblong rectangular box having an open top. This back consists of a base-plate 10, having its ends upturned, as shown at 11, and the sides 12 13 hinged to the base-plate, as shown at 17, so that they may be thrown down into the same 35 plane as the base 10. The back is covered with cloth or leather, as shown at 14, and to this cover is attached the side boards 15 16, so that they are hinged at 16 16. The side plates 12 13 are controlled by means of a shaft 40, journalled centrally in one or both of the end plates 11 and carrying a cross-arm or pair of oppositely-disposed crank-arms 19, which are connected with the side plates by means

of links 20 21, respectively. To each of the side plates is rigidly attached a pair of curved 50 impaling-prongs 22 23, their lengths being approximately equal to the width of the back. The side plates are locked in their closed position by means of a spring-catch 24, secured to one of the end plates 11 by a rivet and having a hook for engaging the aperture 25 in the cross-bar 19. This spring-catch is controlled by a thumb-stud 26, projecting through the end plate.

The shaft 18 may be of the same length as 60 the back and journalled in both of the end plates 11, in which case it may be provided with a cross-bar 19 at each end, as shown in Fig. 1, each cross-bar being connected with the side plates by the links 20 21. This form 65 of shaft is preferably used on large binders and has one of its ends prolonged through the end plate 11 and squared, as shown at 27, for the engagement of a suitable key. (Not shown.)

In smaller binders it may be preferred to use a short stud-shaft, as shown at 28, which projects through but one of the end plates, and in this case the shaft is preferably provided with a permanently-attached thumb-piece 70 75 29, by which it may be turned.

In use the sheets, being preferably suitably apertured, are fitted upon one pair of impaling-prongs, as 22, while the binder is open, as in Fig. 5. The side plates are now closed 80 by turning the shaft 18 or 28, and the curvature of the two sets of impaling-prongs being identical the oppositely-disposed prongs 23 enter the previously-provided apertures in the sheet, and as the side plates close against 85 the end plates 11 the spring-catch 24 engages the aperture 25, and the binder is thus secured in its closed position. The device now constitutes a book which may be used as any ordinary book. The leaves may be removed 90 by again opening the binder, all of the sheets on one side of the leaf to be removed being first shifted to one side thereof and all of the sheets on the opposite side of this sheet being removed to the other side of the binder, 95 so that as the latter opens each set will be

held by a different pair of impaling-prongs, leaving the intermediate sheet free for removal.

I claim as my invention—

- 5 1. In a loose-leaf binder, in combination, a base, end plates, side plates hinged to the base and each carrying impaling-prongs, a rock-shaft journaled in one of the ends and having oppositely-disposed crank-arms, and a link 30 connecting each of the crank-arms with one of the side plates.
- 10 2. In a loose-leaf binder, in combination, a base, end plates, side plates hinged to the base and each carrying impaling-prongs, a rock- 35 shaft journaled in the ends and having a pair of oppositely-disposed crank-arms at each end of the shaft, and a link connecting each of the crank-arms with one of the side plates.
- 15 3. In a loose-leaf binder, in combination, a base, end plates, side plates hinged to the base and each carrying impaling-prongs, a rock- 40 shaft journaled in one of the ends and having oppositely-disposed crank-arms, a link connecting each of the crank-arms with one of the side plates.
- 20 4. In a loose-leaf binder, in combination, a base, end plates, side plates hinged to the base and each carrying impaling-prongs, a rock- 45 shaft journaled in one of the ends and having oppositely-disposed crank-arms, a link connecting each of the crank-arms with one of the side plates, and a spring-catch for locking the shaft against rotation.
- 25 5. In a loose-leaf binder, in combination, a

base, end plates, side plates hinged to the base and each carrying impaling-prongs, a rock-shaft journaled in one of the ends and having 30 oppositely-disposed crank-arms, a link connecting each of the crank-arms with one of the side plates, and a spring-catch secured to the end plate and engaging one of the crank-arms.

35 5. In a loose-leaf binder, in combination, a base, end plates, side plates hinged to the base and each carrying leaf-engaging means, a rock-shaft journaled in one of the ends and having oppositely-disposed crank-arms, and 40 a link connecting each of the crank-arms with one of the side plates.

6. In a loose-leaf binder, in combination, a base, a journal-bearing supported by the base, a rocker-shaft journaled in the bearing and 45 having a crank-arm, a plate oscillating about a fixed center, an impaling-prong carried by the plate, and connection between the crank-arm and the oscillating plate.

CHARLES R. NELSON.
